CYLINDER HEAD FOR HOT-GAS RECIPROCATING ENGINES

Jacobus Albertus Louisa Yzer, Eindhoven, Netherlands, assignor to Hartford National Bank and Trust Company, Hartford, Conn., as trustee

Application August 4, 1950, Serial No. 177,602
In the Netherlands August 9, 1949

4. Claims. (Cl. 60—24)

1

This invention relates generally to hot-gas reciprocating engines which, in the present case are to be understood to include hot-gas reciprocating machines and refrigerating machines operating according to the reversed hot-gas reciprocating engine principle. More particularly, the invention relates to a novel heater head construction for such engines.

In the constructions hitherto known, the cylinder containing the piston or displacer, is surrounded by a second cylinder bounding the working space of the engine. This second cylinder generally comprises channels for the working medium of the engine. These channels form part of the channel system of the heat exchanger associated with the working space. Because of the regularly occurring comparatively high cycle pressure of the engine, the second cylinder must have a comparatively strong wall. Such a strong wall is normally furnished by the provision of a thick wall, due to which the engine head is comparatively heavy. This may sometimes constitute a disadvantage if, for example, the engine is required to have a small weight. This is of more particular importance in regard to traction engines, and notably those to be used as aircraft engines.

In several constructions, the exchange of heat to the working medium of the engine occurs through the wall of the aforesaid cylinder and so is adversely affected by the considerable thickness of this wall.

The present invention has for its purpose to provide the head of a hot gas reciprocating engine with a wall having a small thickness and yet a sufficient strength to withstand the aforesaid engine pressures. To this end, the hot-gas reciprocating engine according to the invention has the feature that the wall of the engine head, which is subject to the intermittent internal pressures of the working medium, is made substantially in the form of part of a sphere extending past its meridian section.

In this manner it is ensured that the wall formed as part of a sphere has a small thickness coupled with sufficient strength to withstand the comparatively high cycle pressure. In addition, as stated above, the heat transfer through this wall is materially improved due to its smaller thickness.

In a suitable embodiment, the space bounded by the wall formed as part of a sphere comprises channels for the working medium of the engine. These channels form part of one or more heat exchangers of the engine.

Since a comparatively high temperature and pressure prevail in the heated space of the hot-gas reciprocating engine, the wall bounding the working space is heavily loaded, as indicated hereinbefore. Additionally, this wall is subject to

2

comparatively high strains due to heat expansion. If this wall is secured to other constructional parts of the engine where the temperature is comparatively high, severe temperature strains may also occur at these points of attachment. In order to avoid this, the hot-gas reciprocating engine according to the invention has the feature that the wall in the form of part of a sphere surrounds the hot-space of the engine at least in part, and the said wall is secured to one or more other constructional parts of the engine at a cold area of the latter.

In various embodiments of this engine, there may be a comparatively great clearance volume in the space bounded by the wall formed as part of a sphere, by which the efficiency of the engine is adversely affected. Therefore, in general, it will be of importance that, according to one embodiment of the invention, the space bounded by the aforesaid spherically shaped wall is partly occupied by filling pieces. Of course, the latter may be solid or hollow.

In a suitable embodiment of the invention, the spherically shaped wall comprises means for increasing the heat transfer from the wall to the working medium. For example, projections or tubes for indirect heating may be included therewith to thus increase the heat transfer through the wall. The wall may alternatively be provided with tubes containing a heat-transmitting medium, thus ensuring indirect heating of the working medium.

In order that the invention may be more fully understood and readily carried into effect, it will now be described in detail with reference to the accompanying drawing, given by way of example, wherein:

Figure 1 is a vertical cross-sectional view, taken along section line I—I of Figure 2, of the cylinder of a hot-gas engine showing a heater head with one embodiment of the invention applied thereto wherein substantially no heat exchange occurs through the wall formed as part of a sphere;

Figure 2 is a horizontal cross-sectional view of the cylinder shown in Figure 1 and taken along section line II—II therein; and

Figure 3 is a vertical cross-sectional view of the cylinder of a hot-gas engine showing a heater head with another embodiment of the invention applied thereto wherein the heat exchange does occur substantially through the wall formed as part of a sphere.

In the cylinder 1 shown in Figures 1 and 2, a displacer 2 and a piston 3 reciprocate in conventional manner. The displacer and piston are linked to a crank shaft in a known manner (not shown) and reciprocate with the usual constant phase difference. The space above the displacer 2 is the hot space, whereas the space

between the displacer 2 and the piston 3 is the cold space. The hot space is surrounded by a wall 4 formed as part of a sphere which extends past its meridian section. The space bounded by the said wall 4 is provided with the channels of a heat exchanger. These channels comprise both the open-topped channels 5 for the combustion gases and the channels 6 for the working medium. The channels 5 and 6 are separated in alternate relationship by common walls 13. With this heat exchanger, the exchange of heat between the combustion gases and the working medium takes place substantially through the aforesaid common walls 13 of the channels 5 and 6. It will be apparent that a much smaller amount of heat exchange will occur through the portions of the cylinder wall 14 bounding the channels 5 at their inner peripheries. The combustion gases enter the heater at 7 and follow the contour of the wall 4 in a radially directed passageway defined between the said wall 4 and a similarly shaped wall 16 spaced therefrom. The flow of the combustion gases in the substantially radial direction is ultimately stopped by an annular deflecting plate 17 which has elongated tongs 15 extending into each of the open-topped channels 5 to just short of the bottoms 18 thereof. Thus, there is caused a doubling back of the flow of the combustion gases in the said channels 5 prior to their final exit via the outlet 8. The working medium flows through the channels 6 and passes through the regenerator 9 and cooler 10 to the cold space; the communication between said channels 6 and the hot chamber being the apertures 19. The clearance in the part of a sphere portion, which is not occupied by the channels of the heat exchanger just described hereinbefore, is filled with parts 11, so that the clearance volume may be comparatively small.

The wall 4 of the engine head is secured to other constructional parts of the engine at a cold area; namely, at a point level with the cold terminal surface of the regenerator as by means of the flange 12 and bolts 21.

In the embodiment of the invention shown in Figure 3, parts similar to those shown in Figure 1 bear the same reference numerals. In this second embodiment, the combustion gases enter the heater at 7 and escape at 8 as before. However, they do not dip into channels such as channels 5 in Figure 1, none being present. Instead, they pass over the spherically shaped wall 4 and give off their heat to the working medium through ribs 20 fixed to the said wall 4. Ribs, indicated at 20', may be fixed to the walls of channel 6 for better heat exchange with the working medium therein. The latter passes through channels 6, regenerator 9 and cooler 10 to the cold space in the usual manner. In this embodiment, also, the space bounded by the spherically shaped wall 4 is filled in part with members 11, thus minimizing the clearance volume. Here, however, the filling members 11 are on the inner sides of the channels 6 so that direct exchange through the wall 4 is possible over the entire surface thereof.

In this embodiment, the wall 4 of the engine head is likewise secured to other constructional parts of the engine at a cold area; namely, on a level with the cold terminal surface of the regenerator, by means of a flange 12 and bolts 21.

It will be appreciated that, in addition to the aforesaid constructions of the heat exchangers

per se, that is, the channel and heat exchange surface arrangements, many different constructions may be used.

What I claim is:

- 5 1. A hot-gas reciprocating engine comprising a cylinder enclosing a hot area and a cold area, means separating said hot and cold areas, an engine head, said engine head having a wall surrounding part of said hot area and being subjected to the internal pressure of the working medium enclosed thereby, means securing said wall to the engine at said cold area, said wall being shaped substantially as part of a sphere across the meridian section thereof.
- 10 2. A hot-gas reciprocating engine comprising a cylinder enclosing a hot area and a cold area, means separating said hot and cold areas, an engine head, said engine head having a wall surrounding part of said hot area and being subjected to the internal pressure of the working medium enclosed thereby, means securing said wall to the engine at said cold area, said wall being shaped substantially as part of a sphere across the meridian section thereof and heat
- 15 25 exchanger means in said head for said working medium, said heat exchanger means comprising channels in a space bounded by said wall.
- 30 3. A hot-gas reciprocating engine comprising a cylinder enclosing a hot area and a cold area, means separating said hot and cold areas, an engine head, said engine head having a wall surrounding part of said hot area and being subjected to the internal pressure of the working medium enclosed thereby, means securing said wall to the engine at said cold area, said wall being shaped substantially as part of a sphere across the meridian section thereof, heating means on one side of said wall, and heat exchanger means in said head for transferring heat
- 35 40 from said heater to said working medium in the hot area, said heat exchanger means comprising channels in a space bounded by said wall.
- 45 4. A hot-gas reciprocating engine comprising a cylinder enclosing a hot area and a cold area, means separating said hot and cold areas, an engine head, said engine head having a wall surrounding part of said hot area and being subjected to the internal pressure of the working medium enclosed thereby, means securing said wall to the engine at said cold area, said wall being shaped substantially as part of a sphere across the meridian section thereof, heating means on the external side of said wall, said heating means having an inlet opening at the meridian point of said wall, said wall having projections thereon for increasing the heat transfer qualities thereof, and heat exchanger means in said head for transferring heat from said heater to the working medium in the hot area, said heat exchanger means comprising channels in a space bounded by said wall.
